UNITED STATES PATENT OFFICE.

LE ROY A. CRUMLEY, OF NEW YORK, N. Y., ASSIGNOR TO THE ROGERS SILVER PLATE CO., A CORPORATION OF CONNECTICUT.

DESIGN FOR BACKPLATE FOR LIGHTING FIXTURES.

Application filed March 24, 1924. Serial No. 9,049. Term of patent 7 years.

To all whom it may concern:

Be it known that I, LE ROY A. CRUMLEY, a citizen of the United States, and a resident of the county of Bronx, city and State of New York, have invented a new, original, and ornamental Design for Backplate for Lighting Fixtures, of which the following is a specification, reference being had to the accompanying drawing, forming a part hereof.

The drawing shows an elevational view of the back plate for lighting fixtures.

I claim:

The ornamental design for backplate for lighting fixtures substantially as shown.

LE ROY A. CRUMLEY.

Witnesses:

JOHN M. COLE,
GAETANO ZAMPARIELLO.
